JACK FOR POSITIONING MATCHED PLANKING

Filed Dec. 4, 1948

UNITED STATES PATENT OFFICE

2,518,586

JACK FOR POSITIONING MATCHED PLANKING

Roy Williamson, Dallas, Tex., assignor of one-half to W. C. Royer, Dallas, Tex.

Application December 4, 1948, Serial No. 63,523

6 Claims. (Cl. 254—14)

1

This invention relates to carpenters' jacks and clamps and it has particular reference to a clamping jack for positioning matched planking in the construction of walls, laying of floors and other such uses.

The principal object of the invention is to improve upon other known types of tools employed to force matched boards into position for nailing by providing, first: a mounting plate supporting a ratchet thrust bar having a bifurcated work engaging head and a lever actuated dog for advancing the bar. Second: a minor and a major clamping means arranged on the mounting plate, the minor clamp being effective to hold the tool on horizontal as well as vertical timbers such as floor and ceiling joists and studs, said major clamp serving to resist movement of the mounting plate as the thrust bar is advanced against the work. Third: means to automatically release the thrust bar and to return the same to inoperative position. Fourth: to provide an attachment for supporting shiplap and like timbers preliminary to nailing onto vertical supports, and fifth, an attachment adapted to be employed in substitution of the clamping means in laying hardwood flooring on a sub-floor where the latter prohibits the use of the said clamping means.

With the foregoing and other objects in view, the invention has further reference to certain features of accomplishment which will become apparent as the description proceeds, taken in connection with the accompanying drawing wherein:

Figure 1 is a perspective view of a tool constructed according to the invention.

Figure 2 is a fragmentary plan view of the mounting plate showing the major clamp.

Figure 3 is a fragmentary perspective view showing the attachment for supporting matched planking for nailing on wall studding.

Figure 4 is a fragmentary perspective view showing a snubbing attachment for use on level surfaces such as on sub-flooring during overlaying of hardwood flooring, and

Figure 5 is a perspective view of the attachment per se, shown in Figure 3.

Figure 6 is a fragmentary view of the thrust bar and shows the operating dog in longitudinal section to reveal the releasing lug thereunder.

Continuing with a more detailed description of the drawing, reference numeral 10 denotes an elongated metal plate, on one end of which is provided parallel ears 11 perpendicular to the plate. Mounted for longitudinal displacement on the plate 10 is a slide 12 whose forward end extends through a rectangular opening 13 in a boss

2

14 formed on the forward end of the plate 10 and on which the ears 11 are mounted. The said opening 13 serves as a guide for the slide 12. Mounted on the side 12 is a ratchet thrust bar 15 which is made of hollow tubing and contains a coil spring 16, one end of which is secured within the bar while the opposite end is anchored to an eye 17 which latter is mounted on the plate 10 adjacent its rear end. Thus, the thrust bar 15 is normally held in retracted position.

On each side of the plate 10 forwardly of its midsection is formed a pair of ears 18. Between each pair of ears is pivoted at 19 the legs of an inverted U-shaped frame 20, to which is attached a handle 21 by which the frame is oscillated to bring into successive engagement with the teeth 22 of the bar, a dog 23. A torsion spring 24 serves to hold the dog 23 in engagement with the teeth of the bar and pivoted between the forwardly disposed ears 11 is a second dog 25 (Fig. 1) which resists the action of the retracting spring 16. The dog 25 is held in engagement with the teeth of the bar 15 by an expansion coil spring 26, the latter being disposed between the mounting plate 10 and a lever 27. The lever is affixed to a shaft 28 journaled in the ears 11 and on which the dog 25 is mounted and by depressing the lever, the dog is raised against the pressure of spring 26 to lift the same out of engagement with the teeth of the ratchet bar. In order to release the ratchet or thrust bar 15 to the pull of spring 16 which will retract the same a bolt 27a is threaded through the dog 23 and the lower end of this bolt extends below the undersurface of the dog to define a lug 27b (Fig. 6) which is brought into engagement with the upper surface of the thrust bar when the operating handle 21 is moved to the extreme right, as viewed in Figure 1, thus to lift the forward end of the dog out of engagement with the teeth of the thrust bar.

On the forward end of the ratchet or thrust bar 15 is a work engaging head 29 which is substantially U-shaped in transverse section so that it may engage a plank 30 on opposite sides of its tongue 31 or, when the plank is reversed, the head may engage the same on each side of the groove 32 and in either case, the matched edges of the plank are undamaged by the thrust of a tool which is often the case when matched boards are forced in to interlocking relationship by blows of a hammer. In the present case, a recess 33 is provided in the head to accommodate a nail.

It is apparent from the foregoing that when the handle 21 is actuated, the thrust bar 15 is moved longitudinally on the base plate 10 to advance the

head 29 against the work. However, in order that the mounting plate 10 will remain stationary so that the bar will have the full effect to urge a plank into position, a holding means is provided which is referred to herein as a minor and a major clamp. The minor clamp consists simply of a pair of jaws 34, one being pivoted at 35 at each side of the mounting plate 10 to an arm 36 affixed to the latter and serving also as a guide for the slide 12 on which the thrust bar 15 is mounted. The opposite end of each of the jaws is shaped into a handle 37 which are jointly gripped by one hand to expand the jaws 34 against the resistance of an expansion spring 38, housed in a tube 39, the latter being bifurcated at each end to receive the handles 37 and to permit the spring 38 to be compressed within the tube.

The spring 38 is effective to hold jaws 34 in clamped position on a joist 40 or on a wall stud until such time as the bar 15 has been ratcheted to a position of engagement with a board. When this occurs, there is a tendency on the part of the mounting plate 10 to move rearwardly or away from the work, due to the resistance of the work on the bar 15. To preclude this, the major clamp and operating means is provided which consists of a triangular plate 41 affixed to the rear end of plate 10 as by screws 42. This plate 41 serves as a wedge, separating the inner ends of arms 43 of a pair of jaws 44, against the resistance of a coil spring 45 which exerts a pull normally opening the jaws, due to their pivotal mounting at the ends of a cross-member 46.

The cross-member 46 as well as the arms 43 are affixed to a plate 46a by means of screws 46b. The sole connection between the plate 46a and the mounting plate 10 is through the medium of a strap 46c, slotted at S (Fig. 2) to receive a pivotal screw 46d and pivoted at a to the tail of the mounting plate 10. The pivotal connection a enables the plate 46a as well as the jaws 44 to oscillate slightly with respect to the mounting plate 10, limited by the upturned ears b on each side of the plate 46a which engage the sides of the mounting plate, such oscillation permitting the jaws 44 to adjust themselves to a support such as a joist or stud. The slot S in the strap 46c permits longitudinal sliding displacement of plate 46a and jaws 44 with respect to the mounting plate 10.

As the head 29 on the thrust bar 15 is brought up against the work, rearward displacement of the mounting plate results, causing the divergent edges of the wedge 41 to expand the arms 43, thus to contract the jaws 44, whose downwardly and inwardly curved and sharpened ends bite into the sides of the particular timber to which the tool is attached, may it be a joist 40, as shown, a rafter, stud or the like. Therefore further displacement of the tool is interrupted so that continued manipulation of the handle 21 will have the effect to exert full force of the thrust bar against a board to force the same into matching relation with a companion board.

In some cases, it will not be possible to employ either of the clamping devices, such as in laying hardwood flooring over sub-flooring, for the reason that the latter covers the joists. In such a case, the jaws 34 of the minor clamp and jaws 44 of the major clamp are detached from the mounting plate and in place of the latter, a snubbing plate 47 is secured to the underside of the plate 10 at its rear, as by bolts 48. The plate 47 is formed with a downwardly curved and sharpened tongue 49 which is adapted to bite

into the surface of the sub-flooring when rearward pressure is brought to bear on the mounting plate 10 by engagement of the thrust bar against the work, as earlier pointed out. The snubbing plate 47 therefore serves in the place of the major clamping jaws 44 to prohibit rearward displacement of the mounting plate so that the thrust bar will have the full effect to urge a plank into engagement with another.

When laying flooring in places which will not accommodate the tool in the operative position described, such as when nearing a wall or partition, it becomes necessary to reverse the position of the tool so that a pull rather than a push may be exerted on the boards as they are laid. To accomplish this, a pull bar 50 (Fig. 5) is provided, which has a bifurcated hook 51 on one end adapted to receive a cross-head 52 on the rear end of the thrust bar 15. A latch 53 is pivoted at 54 adjacent the hook 51 to prevent displacement of the latter from the cross-head 52 when travel of the thrust bar 15 is reversed in the manner to be presently described. The pull bar 50 carries on its opposite end a hook 55.

To operate the tool in pulling a board into interlocking engagement with a board already nailed to supports, it is necessary to nail to the floor a suitable timber on which the clamp jaws 44 may have purchase. The hook 55 of the pull bar 50 is then placed over the edge of the board to be positioned and the handle 21 is manipulated to move the thrust bar 15. There is a tendency for the mounting plate 10 to move in the opposite direction, which movement is interrupted by the setting of the jaws 44 into the temporary support of the tool, whereupon further movement of the thrust bar 15 will exert a pull on the bar 50 effective to urge the board engaged thereby into position.

After positioning the board, the lever 27 is depressed to release the holding dog 25 and the operating handle 21 moved rearwardly to release the dog 23 as described to permit the thrust bar to return to inoperative position by action of its return spring 16. The pull bar 50 will also be returned to its original position by virtue of the latch 53, previously mentioned, which prevents disconnection of the bar 50 from the thrust bar 15, and the guide 56 (Fig. 3) which holds the bar 50 in axial alignment with bar 15.

The pull bar 50, it will be observed, is tubular and has opposed longitudinal slots 57 therein. Slidable on the bar is a block 58 having integral therewith a protuberance or finger 59 disposed parallel with the bar 50 and directed toward the hook 55 on the end of the latter. The block 58 is held against rotation on the bar by a pin 60 passing through the slot 57 of the bar.

The foregoing arrangement is to adapt the tool for sustaining one end of a board, such as shiplap, in erecting a wall, while the opposite end thereof is being nailed in position on the studs. The tool is manipulated so that one end of a board to be nailed is engaged between the hook 55 of the bar 50 and the finger 59 of the block 58. The tool is then lifted so that the clamp jaws 34 may be engaged with a wall stud. The tool is thus sustained, holding the board in such position at one end that its opposite end may be nailed. Afterwards, the tool may be removed and the end of the board from which it is released may be nailed.

The block 58 is provided with a set screw 61 by which it may be secured against sliding movement on the bar 50.

The attachment last described above is highly advantageous for the reason that boards of considerable length may be nailed in position by a single workman while the efforts of two workmen have hitherto been required for this purpose.

It is clearly evident that the tool may be used with equal facility in positioning boards on inclined supports such as in roofing, or disposing the same in angular positions on upright studs as they are frequently applied in erecting walls.

Manifestly, the construction as shown and described is capable of some modification and such modification as may be construed to fall within the scope and meaning of the appended claims is also considered to be within the spirit and intent of the invention.

What is claimed is:

1. A jack for positioning matched planking for nailing comprising a base plate, a hollow, toothed thrust bar held on said plate against other than longitudinal displacement, a spring in said bar resisting displacement thereof, an interchangeable work engaging head on one end of said thrust bar, a ratchet for advancing said bar against the resistance of said spring, a holding dog displaceable for releasing said bar to the retracting action of said spring, a pair of minor clamping jaws pivoted to said base plate at its midsection for holding the same on a support, a pair of major clamping jaws pivoted for oscillative displacement at the rear end of said base plate and also engageable with said support, means normally expanding said major jaws, said major jaws having rearwardly convergent arms, a wedge affixed to said base plate effective engageable by said arms to expand the same to contract said major jaws on said support to secure said base plate against counter-thrust of said thrust bar upon contact with the work of said work engaging head.

2. A carpenter's jack including a base plate, a hollow thrust bar movable longitudinally on said base plate, a coil spring secured at one end within said bar and at its opposite end to said base plate to resist advancing displacement of said bar, a ratchet for advancing said bar, an interchangeable work engaging head on said bar, a pair of normally contracted, minor clamping jaws at the midsection of said base plate adapted to hold said jack on a support, a pair of normally expanded, major holding jaws mounted for oscillative and longitudinal displacement at the tail of said base plate, said major jaws having inwardly convergent arms rearwardly thereof, a wedge affixed to said base plate adapted to engage and expand said arms effective to contract said major jaws on said support to prohibit movement of said base plate counter to the thrust of said thrust bar against the work and displaceable holding means for releasing said thrust bar to the retraction action of said coil spring to expand said major jaws.

3. A carpenter's jack comprising a base plate, a minor clamping means for holding said base plate on a support in operative relation to the

work, said clamping means comprising a pair of normally contracted jaws pivoted to said base plate at its midsection, a pair of major clamping jaws pivoted for oscillative and longitudinal displacement at the tail of said base plate, and having rearwardly convergent arms, a spring normally expanding said major jaws, a wedge affixed to said base plate, a thrust bar slidable longitudinally on said base plate having a work engaging head, a ratchet operative to advance said bar to urge its head against the work, said wedge being effective to engage and expand said convergent arms to contract said major jaws on said support to interrupt displacement of said base plate caused by the thrust of said bar as the head thereof engages the work and holding means displaceable for releasing said thrust bar from said ratchet to retract the same.

4. In a tool for forcing engagement of the tongue and groove of matched planking, a base plate, a minor and a major clamping means for said base plate, said minor clamping means comprising normally contracted jaws for holding said base plate on horizontal or vertical supports, said major clamping means comprising normally expanded jaws mounted for longitudinal and oscillative movement on the tail of said base plate and adapted to secure the latter against longitudinal displacement on a support, rearwardly convergent arms formed on said major jaws, a thrust bar slidable longitudinally on said base plate and having an interchangeable work engaging head, manually actuated ratchet means for advancing said thrust bar, a spring for retracting said bar, a wedge on said base plate adapted to engage between said convergent arms for contracting said major jaws on the support to prohibit yielding of said base plate when said work engaging head contacts the work and means for holding and for releasing said bar to the action of said retracting spring.

5. In a tool as described in claim 4, a pull bar detachably connected to the rear end of the thrust bar to extend rearwardly of the base plate and provided with a hook to engage work and move the same toward the tool upon advancing action of said thrust bar.

6. In a tool as set forth in claim 4, a snubber plate replacing the major and minor clamping means having an arcuated and sharpened tongue for engagement with a supporting surface to hold the base plate against movement counter to that of the thrust bar.
